Atay

United States Patent Office.

ISAAC SILVERNAIL, OF BYRON, MICHIGAN.

Letters Patent No. 96,277, dated October 26, 1869.

IMPROVED BURGLAR-ALARM.

The Schedule referred to in these Letters Patent and making part of the same.

To all whom it may concern:

Be it known that I, ISAAC SILVERNAIL, of Byron, in the county of Shiawassee, and in the State of Michigan, have invented certain new and useful Improvements in Self-Alarm for Gates and Doors; and do hereby declare that the following is a full, clear, and exact description thereof, reference being had to the accompanying drawings, and to the letters of reference marked thereon, making a part of this specification.

The nature of my invention consists in the construction and arrangement of a self-alarm, to guard against burglars, and is applicable to gates as well as doors.

In order to enable others skilled in the art to which my invention appertains, to make and use the same, I will now proceed to describe its construction and operation, referring to the annexed drawings, in which—

Figure 1 is a side elevation of the entire apparatus, and

Figure 2 is a plan view of the spring that strikes the alarm.

A represents a door or gate, hinged by the hinges B B.

To the lower hinge is attached a small rod, a, which is provided with a pulley or wheel, C.

This wheel is, by a cord, b, connected with a small wheel, D, attached to the large wheel E, which may be mounted in any convenient place, the cord b passing around one or more pulleys, d, so that when the door is opened the cord will revolve the large wheel E.

The wheel D is, by another cord, e, connected with a spring, F, in such a manner that the spring will act in the opposite direction, turning the wheel E so as to close the door as soon as the force is removed from the same.

At a suitable point is suspended or secured a bell, G, which is struck by a wire spring, H, of the peculiar form shown in fig. 2.

At one end it forms a coiled spring, f, secured to a wall, or other suitable support, then bent so as to form the hammer g, which is inserted in the bell G, and its outer end projecting along the front side of the wheel E.

On the front side of this wheel is a series of pins, i i, which, when the door is being opened and the wheel revolves, raises the outer end of the spring H, and as it springs down or back, after it leaves each pin, the hammer-part g strikes the bell G.

This device is very simple, and can be put up in any place desired, and connected either with the upper or lower hinge.

When the apparatus is to be attached to gates, the alarm-mechanism may be placed in the house, and the cord b carried through tubes, so as to make the connection.

Having thus fully described my invention,

What I claim as new, and desire to secure by Letters Patent, is—

1. The wire H, constructed or bent as described, so as to form the coil spring f and hammer g, substantially as and for the purposes herein set forth.

2. The arrangement of the wheel E, provided with pins i i, wheel or pulley D, cords b e, spring F, and pulley C, all substantially as and for the purposes herein set forth.

3. The combination of the gate or door A, hinge B, pulleys C D, wheel E, with pins i i, cords b e, spring F, bell G, and wire H, all constructed as described, and for the purposes set forth.

In testimony that I claim the foregoing, I have hereunto set my hand, this 6th day of September, 1869.

ISAAC SILVERNAIL.
